(57) **CLAIM**

The ornamental design for a small square baler, as shown and described.

DESCRIPTION

FIG. 1 is a top front left side perspective view of a small square baler showing my new design;

FIG. 2 is a front view thereof;

FIG. 3 is a rear view thereof;

FIG. 4 is a left side view thereof;

FIG. 5 is a right side view thereof; and,

FIG. 6 is a top plan view thereof.

The broken lines are for illustrative purposes only and form no part of the claimed design.
